UNITED STATES PATENT OFFICE.

RUDOLPH FAAS, OF CHICAGO, ILLINOIS, ASSIGNOR OF ONE HALF TO
WILLIAM TAUSSIG, OF SAME PLACE.

CAR-AXLE BOX.

SPECIFICATION forming part of Letters Patent No. 352,612, dated November 16, 1886.

Application filed August 2, 1886. Serial No. 209,740. (No model.)

To all whom it may concern:

Be it known that I, RUDOLPH FAAS, a citizen of the United States, residing in the city of Chicago, county of Cook, and State of Illinois, have invented a new and useful device and Improvement for Lubricating Journals on Car-Axes, of which the following is a specification.

The usual method of lubricating car-axes is by filling the axle-box with cotton-waste and oil, the saturated waste coming in contact with the journal. This method is not only wasteful, but liable to convey to the journal sand or other foreign matter, causing increased friction, and frequently fails to provide sufficient lubricant. Ignition and combustion follow under certain conditions, not necessary to explain in this specification.

March 16, 1886, Letters Patent No. 338,051 were issued to me for an improved car-axle lubricator, which consisted of a roller placed yieldingly underneath the journal in the car-axle-box, and operating on the journal, being held in its position by elliptic springs.

This invention, while it is an improvement on my patented invention above mentioned, is in all respects, except as to the use of a roller similarly located with reference to the car-axle journal, practically a new device, and differs as to its construction as well as to its utility.

The objects of my improvements are, first, to provide a continuously-lubricated axle-journal; second, to economize in the consumption of the lubricant, and, third, to confine and protect the lubricant from accumulations or deposits of sand, dust, or other foreign matter. I attain these objects by the mechanism illustrated in the accompanying drawings, in which—

Figure 1 is a vertical cross-section of a car-axle box, showing the relation of my device thereto and to the journal. Fig. 2 is a plan view of frame and roller removed, with end broken to show details in construction. Fig. 3 is a vertical sectional end view on line 3, Fig. 2, exhibiting the roller bearing upon the spiral spring. Fig. 4 is a perspective end view of the roller in its adjustable bearings.

Similar letters refer to similar parts throughout the several views.

A is the journal of the car-axle.

B is the car-axle journal-box.

C is the journal-bearing.

D D is a metal frame containing the roller.

E is the roller, of cork, paper, leather, felt, 55 or other material.

F is a spiral spring placed under each end of the roller and against which it acts.

G is a self-adjusting cover, which has one side fastened on the upper edge of the roller-frame D D, and extends over upon the apron or roller-guards.

H is the extension of the frame to the opposite side of the journal-box, which serves the double purpose of securing the roller-frame 65 firmly in its position, and enables me to place a cover over the lubricant and inclosing it.

K is a loose metal cover over the frame H.

O is the lubricant in the journal-box proper, and inclosed in the roller-frame D D and extension H and cover K.

a a are aprons or guards partially inclosing the roller E.

c is a receptacle for the blocks d d.

d d are the blocks which enter the receptacle 75 c, and on which rests the roller E.

e e are grooves in the ends of roller-frame D D, from which the frame is constructed by the sides H to the opposite side of the journal-box, thus inclosing the lubricant.

x x are set-screws which engage in the flanges y y.

y y are the flanges on the end of the roller or spool.

z z is a rod with a thread on each end connecting the flanges y y.

In the construction of my device I place the roller E about two inches (more or less) above the bottom of the car-journal box, and when not submerged on the lubricant relying upon the motion of the wheel to agitate the lubricant against the roller E, which is protected on its upper half-circle by an apron or guards, a a, which may consist of any metal, the same being for the purpose of keeping the roller E 95 in position, and allowing a segment of the roller to be presented to the journal A of the car-axle, thereby economizing in the amount of the lubricant served to the journal, the roller E and its covering or apron a a being 100 combined and together resting on a frame, D D, of any desirable metal, said frame D D being

placed in the journal-box B at either side, or, if two lubricators are preferred, one on each side of the journal A in the journal-box B, thus allowing the roller E to bear upon the 5 journal's periphery at an angle of about forty-five degrees (more or less) from the frame of my device, the bottom of the frame D D being open, allowing the roller E to play freely in the lubricant O underneath it, or to come in 10 contact with it by agitation.

Attached to the roller E, by the set-screws x x, are the square blocks d d, the said blocks working freely in their receptacles C in the frame D D, surrounding the roller E, operating 15 somewhat as a block would work in a link. In the link-motion only we obtain the pressure upon the blocks by means of the spiral springs F, thus keeping it constantly in contact with the journal of the axle. The blocks d d are 20 countersunk sufficiently to receive the spiral springs F and to embed themselves therein, thus preventing them from being crushed.

The roller E may consist of cork, paper, which is porous and firm, leather, felt, or other 25 compact fibrous material, or any other substance having a capillary attraction sufficient to raise and hold the lubricant and serve the journal A, as described. The reason I desire a porous roller, or one having capillary attraction, is to hold in the pores of the roller more or less of the lubricating material after the supply in the box is exhausted, which may then be served to the journal.

In the use of one in place of two lubricators 35 of my construction, I protect the lubricant O in the journal box B, Fig. 1, from receiving dust and other foreign matter. In order to accomplish this, I make a groove, e, in each end at the bottom of my lubricator-frame, allowing 40 me to construct therefrom a box or covering for the lubricant, simply by forming a square frame, H, Fig. 1, the two end pieces connected with a similar piece parallel with the axle A or my lubricator-frame, but bearing upon the 45 opposite side of the axle-box at o, Fig. 1, to which my frame is attached, thus enabling me to use a light covering, K, of sheet-iron or any other material I may desire to use, placed upon the described frame. This excludes all 50 dust or foreign matter, and will prevent the lubricant from being shaken out of the journal-box or displaced. It will be understood that the cover K is free and readily removed when necessary to replenish the lubricant or 55 for any other purpose. Instead of swinging the roller E upon an ordinary axis in said frame, I place two blocks, d d, playing in corresponding receptacles, through which blocks I place set-screws x x, engaging in the flanges 60 y y of the roller proper, the flanges y y being centered and countersunk for that purpose, thereby enabling me to take up any lost motion that may occur to the roller E. The rod

or spindle z, having a thread on each end, connects the flanges y y. On the top of the roller-frame D D, Fig. 1, is fastened a metal self-adjusting cover, G, with its one edge resting on the apron or roller guards a a, which incloses the elevated portion of the roller E and frame D D, and with the cover K lying underneath the journal A on the frame H, completely incloses the lubricant O in the journal-box B.

I am aware that prior to my invention lubricators have been made by having rollers 75 operate against the journal, and therefore I do not claim such a combination, broadly; but

What I do claim as my invention, and desire to secure by Letters Patent, is—

1. The combination of the roller E with 80 the metal frame D D, open upon the bottom to permit the roller E to play in or receive the lubricant which is then served upon the journal A, substantially as set forth.

2. The combination of the roller E, consisting of cork, leather, felt, cloth, paper, or other porous substance for receiving, holding, and serving the lubricant to the journal A, with the metal frame D D and extension H H, substantially as above described and set forth. 90

3. The combination of the roller E, partially covered and protected by the guards or aprons a a, bearing upon the blocks d d, resting upon the spiral springs F F, operating upon the journal A, substantially as described. 95

4. The combination of the roller E with the frame D D and extension H H, with the cover K and adjustable spring-cover G, for the purpose of keeping the journal continuously lubricated and of protecting the lubricant 100 from dirt, sand, or other foreign material, substantially as set forth and described.

5. The combination of the roller E, having capillary attraction, with the apron or guards a a, the blocks d d, the set-screws x x, the 105 flanges y y, centered and countersunk, the rod z, the spiral springs F F, the frame D D and H H, and covers G and K, substantially as described, for the purpose specified.

6. The combination of the roller E on its 110 frame D D, its adjustable bearing, and protected with its aprons or guards, as above described, with the device resting upon the bottom of and in the lower corner of the journal-box and upon my device B, Fig. 1, which allows the roller E to engage with the journal A at an angle of about forty-five degrees, (more or less,) as above described, thereby allowing the journal to play freely in the journal-box without injury to my roller and frame, substantially as set forth. 115 120 125

Corrections in Letters Patent No. 352,612.

It is hereby certified that in Letters Patent No. 352,612, granted November 16, 1886, upon the application of Rudolph Faas, of Chicago, Illinois, for an improvement in "Car-Axle Boxes," errors appear in the printed specification requiring the following corrections: In line 90, page 1, the word "on" should read *in*; in line 15, page 2, a comma should be substituted for the period after the word "link;" and the following word "In" should commence with a small *i* making a continuous sentence; in line 16, same page, a comma should be inserted after the compound word "link-motion;" in line 115, same page, the words "and upon my device" should be stricken out and inserted at the end of line 119; and that said Letters Patent should be read with these corrections therein that the same may conform to the record of the case in the Patent Office.

Signed, countersigned, and sealed this 14th day of December, A. D. 1886.
